HOUSING FOR HOLDING DEODORIZING MEDIUM

Arthur Kagan, 5019 W. Van Buren St., Chicago, Ill.

Filed Sept. 22, 1961, Ser. No. 66,807

Term of patent 14 years

(Cl. D16—2)

FIG. 1 is a front elevational view of a housing for holding deodorizing medium embodying my new design; FIG. 2 is a side elevational view thereof; FIG. 3 is a top plan view thereof; FIG. 4 is a bottom plan view thereof; and FIG. 5 is a rear elevational view thereof.

The dominant features of my design reside in the portions shown in full lines.

I claim:

The ornamental design for a housing for holding deodorizing medium, substantially as shown and described.
